(57) **CLAIM**

The ornamental design for an optical connector ferrule, as shown and described.

DESCRIPTION

FIG. 1 is a right, top perspective view of an optical connector ferrule showing my new design;

FIG. 2 is a left, bottom perspective view thereof;

FIG. 3 is a front elevation view thereof;

FIG. 4 is a left elevation view thereof;

FIG. 5 is a right side elevation view thereof;

FIG. 6 is a top plan view thereof;

FIG. 7 is a bottom plan view thereof;

FIG. 8 is a cross sectional view thereof, taken along line 8-8 of FIG. 6;

FIG. 9 is a cross sectional view thereof, taken along line 9-9 of FIG. 6;

FIG. 10 is a cross sectional view thereof, taken along line 10-10 of FIG. 6;

FIG. 11 is a right, top perspective view thereof as a reference; and,

FIG. 12 is a left side elevational view thereof as a reference. The broken line in the drawing views is for the purpose of illustrating unclaimed environment structure and forms no part of the claimed design.
